UNITED STATES PATENT OFFICE.

CHARLES A. GILMORE, OF McCOMB, MISSISSIPPI.

FEED-WATER HEATER.

1,363,773.

Specification of Letters Patent. Patented Dec. 28, 1920.

Application filed May 4, 1915. Serial No. 25,750.

To all whom it may concern:

Be it known that I, CHARLES A. GILMORE, a citizen of the United States, residing at McComb, in the county of Pike and State of 5 Mississippi, have invented certain new and useful Improvements in Feed-Water Heaters; and I do hereby declare the following to be a full, clear, and exact description of the invention, such as will enable others 10 skilled in the art to which it appertains to make and use the same.

My invention relates to improvements in boilers especially adapted for use on locomotive and other steam engines and has for 15 its primary object the provision of inexpensive means by which the water will be quickly heated and converted into steam so that fuel economy will be permitted.

Another object of importance is to provide feed water heater means of the character described which includes a number of pipes that are arranged within the fire box and operatively connected with the boiler and inlet pipe therefor in such manner that 25 the water is heated prior to being admitted to the boiler and the cold water at the lower part of the boiler caused to circulate and be heated thus providing an expeditious heating of the water and causing it to be 30 readily converted into steam.

This invention further aims to improve steam boilers, so as to render them more practical and efficient, inexpensive to maintain in working condition and operate and 35 resides in the provision of extremely simple and reliable feed water heating means that may be readily attached to locomotives and other steam boilers without necessitating any material change in the construction of 40 the boiler.

With these and other objects in view the invention consists in the construction and novel combination and arrangement of parts hereinafter fully described, illustrated 45 in the accompanying drawings and pointed out in the claims hereto appended, it being understood that various changes in the form, proportion and minor details of construction may be resorted to without departing from 50 the spirit or sacrificing any of the advantages of the invention.

In the drawings—

Figure 1 is a side elevation showing the feed water heating means in diagram and 55 attached to a locomotive boiler,

Fig. 2 is a fragmentary detail sectional view of the coupling member to connect the several pipes of the device with the boiler and feed pipe thereof,

Fig. 3 is a longitudinal fragmentary sectional view of a boiler showing my feed water heating means in position therein and being broken away in part,

Fig. 4 is a vertical sectional view taken on line 4—4 of Fig. 3,

Fig. 5 is a plan view of the distributing reservoir.

Like numerals of reference designate corresponding parts in all the figures of the drawings:

In the accompanying drawings, which illustrate the preferred embodiment of my invention, 1 designates the back head, 2 the crown sheet, 3 the outer shell, 4 the fire tubes, and 5 the firebox of a locomotive boiler of 75 a well known construction. Arranged on each side of the boiler, and leading from any well known form of injector, not shown, is a water inlet or feed pipe 6'. These pipes are provided with swinging check valves 7 of any well known construction. Vertical pipes 9 are connected at their upper ends with the feed pipes 6' adjacent the check valves 7, and they extend to a point beneath the boiler where they are connected to coupling members 10. The coupling members 10 are each provided with a plurality of nipples 11, 11^a, 11^b, and 11^c. The upper nipples 11 are screw threaded exteriorly as at 12 and turned within openings formed in the under 90 side of the outer shell 3 in advance of the throat sheet 12^a. The lower nipples 11^b are provided with plugs 13 which may be removed when it is desired to clean the coupling members and other parts of the device. The lower ends of the pipes 9 have threaded engagement with the walls of openings 14 formed in caps 15 threaded upon the nipples 11^a. Injector nozzles 16 have their forward ends threaded into the openings 14 and communicate with the pipes 9. The injector nozzles 16 are of considerably less diameter than the nipples 11^a and 11^c through which they extend, and they are approximately of the same diameter as the pipes 9. 105 The rear ends of the injector nozzles 16 extend into pipes 17^a which connect the coupling members 10 to the front sides of a water distributing reservoir 18 and which establish communication between the cou-

110

pling members and the reservoir. The nipples 11^c are threaded upon the front ends of the pipes 17^a, the parts being held in firm connection by jam nuts 18 which are threaded upon the pipes 17^a and which engage the nipples 11^c. The distributing reservoir 18^a which is provided with an attaching flange 18^b, is located beneath and bolted to the under side of boiler between the throat 5 sheets 12^a and the coupling members 10. A lower series of heating pipes 17 and an upper series of heating pipes 22, which communicate with the rear side of the reservoir 18^a, extend upwardly and rearwardly 10 through the throat sheet 12^a and tube sheet 12^b into the fire box 5. The upper ends of the heating pipes 17 and 22 pass through the back sheet 1 and communicate with the waterspace between this sheet and the back head 15 1. The upper rear ends of the pipes 17 and 22 are flared or rolled as at 20 to engage the rear side of the back sheet 1^a and prevent leakage into the firebox. To prevent leakage at the points where the pipes 17 and 22 20 pass through the throat sheet 12^a and tube sheet 12^b, sleeves 21 are provided. These sleeves have their ends flared or rolled to establish a liquid tight connection with the tube and throat sheets. The rear side of the 25 reservoir 18^a is provided with an upper series and a lower series of short pipe sections 17^b which communicate with the reservoir and which extend rearwardly therefrom. These pipe sections are provided with 30 unions 17^c which have threaded engagement with the front ends of the pipes 17 and 22. To enable the pipes 17 and 22 to be cleaned, removable plugs 24 are arranged in the back head 1 in alinement with the rear 35 ends of the pipes. By removing the plugs 13 and the plugs 24, the entire device may be cleaned.

The location of the reservoir 18^a beneath the boiler in advance of the throat sheet 12^a, and 40 the location of the coupling members 10 beneath the boiler in advance of the reservoir 18^a, causes water to circulate in a rearward direction through the coupling members 10, the pipe sections 17^a, the reservoir 18^a, the pipe sections 17^b and the pipes 17 and 22; prevent the reservoir, coupling members, pipe sections 17^a, pipe sections 17^b and unions 17^c from being affected by the heat 45 of the firebox; and permit easy access to these parts. As the injector nozzles 16 extend beyond the coupling members 10 into the pipe sections 17^a, the flow of the feed water will not interfere with the circulation 50 of the boiler water through the couplings 10, pipe sections 17^a, reservoir 18^a, pipe sections 17^b and pipes 17 and 22. The front ends of the injector nozzles 16 are connected to the feed water pipes 9.

To increase the effectiveness of the feed 55 water heating means, I provide a fire arch

25 that is preferably composed of brick and arranged upon the pipes 22 as shown in Figs. 3 and 4 of the drawings.

The arch 25 is so arranged that the flames 70 from the fire in the fire box will extend upwardly in a rearwardly inclined plane and then forwardly thus providing intense heat adjacent to the pipes 17 and 22 and returning a certain amount of the heat to the arch so that the pipes will be readily heated. 75

In operation all the water is fed to the boiler through the feed pipes 9, nozzles 11, and pipes 17 and 22. The water at the lower part of the boiler is the coldest and as the water in the pipes 17 and 22 is at a higher 80 temperature, the weight of the cold water in the lower part of the boiler will force the water down through the coupling 10 and into the distributing reservoir and up through the heating pipes 17 and 22 when 85 the injector of the ordinary feed water system (not shown) is shut off. When the injector is operating the water will pass through the feed pipes 6' and 9 and through the coupling 10 into the distributing reservoir 90 and then through the pipes 17 and 22 to the boiler. It will thus be seen that a circulatory system is provided and that the water will be thoroughly heated prior to its admission to the boiler. 95

In practice I have found that the form of my invention illustrated in the drawings and referred to in the above description, as the preferred embodiment, is the most efficient and practical; yet realizing that the 100 conditions concurrent with the adoption of my device will necessarily vary, I desire to emphasize the fact that various minor changes in details of construction, proportion and arrangement of parts may be resorted 105 to, when required, without sacrificing any of the advantages of my invention, as set forth.

What is claimed is:—

1. In a feed water heater, the combination 110 with a locomotive boiler and its firebox, of water heating pipes arranged in the firebox and having their rear ends communicating with the water space between the back head and the back sheet of the firebox and having 115 their front ends extending through the tube and throat sheets of the boiler, a water distributing reservoir located beneath and secured to the under side of the boiler in advance of the front ends of the heating pipes, 120 means establishing communication between the front ends of the pipes and the reservoir, a coupling located beneath and secured to the boiler in advance of the reservoir and communicating with the bottom of the 125 boiler, means establishing communication between the coupling and the reservoir, and injector nozzles extending rearwardly through the coupling, and a feed pipe communicating with the front end of the nozzle. 130

2. In a feed water heater, the combination with a locomotive boiler and its firebox, of water heating pipes arranged in the firebox and having their rear ends communicating with the water space between the back head and back sheet of the firebox and having their front ends extending through the tube and throat sheets of the boiler, a water distributing reservoir located beneath 5 and secured to the under side of the boiler in advance of the front ends of the heating pipes, pipe sections carried by the rear wall of the reservoir and communicating with the reservoir, unions connecting the pipe sections and the front ends of the heating pipes, a pipe section carried by the front wall of the reservoir and communicating with the reservoir, a coupling located beneath and secured to the under side of the boiler in advance 10 of the reservoir and communicating with the bottom of the boiler, a union connecting the front pipe sections and coupling, an injector nozzle passing rearwardly through the coupling into the front pipe section, and a feed pipe communicating with the front end of the injector nozzle.

3. In a feed water heater, the combination with a locomotive boiler and its firebox, of a water distributing reservoir located beneath the boiler in advance of the firebox, water heating pipes extending rearwardly from the reservoir into the firebox and communicating at their rear ends with the water space between the back head and back sheet 15 of the firebox, a coupling located beneath the boiler in advance of the reservoir and communicating with the bottom of the boiler, means establishing communication between the coupling and reservoir, an injector nozzle passing rearwardly through 20

the coupling into said means, and a feed water pipe communicating with the front end of the injector nozzle.

4. In a feed water heater, the combination with a locomotive boiler and its firebox, of water heating pipes arranged in the firebox and having their rear ends secured to the back sheet and communicating with the water heating space between that sheet and the back head and having their front ends extending through the tube and throat sheets, said back head being provided with openings alining with said heating pipes, plugs removably secured in said openings, a water distributing reservoir secured to the under side of the boiler in advance of the front ends of the heating pipes, pipe sections carried by the rear wall of the reservoir and communicating with the reservoir, unions detachably connecting the pipe sections and front ends of the heating pipes, a coupling removably secured to the under side of the boiler and communicating with the bottom thereof, a pipe section carried by the front wall of the reservoir and communicating therewith, a union detachably connecting the front pipe section to the coupling, an injector nozzle passing rearwardly through the coupling into the front pipe section, and a feed pipe communicating with the front end of the injector nozzle and detachably connected thereto, and a removable plug closing the lower side of the coupling. 45 50 55 60 65 70

In testimony whereof I affix my signature in presence of two witnesses.

CHARLES A. GILMORE.
